[57] ABSTRACT

A receptacle attachment comprising a case adapted for fixed mounting to a wheelchair arm and defining a main compartment for receiving sundry articles. A cover pivotally mounted to the case includes a front wall having a lower edge portion engageable upon the case front wall to orient the cover in a horizontal or open position in which its walls define an auxiliary compartment adjacent the main compartment. Resilient snubbers releasably hold the cover in its closed position.

FIG.1

FIG. 2

FIG. 3

FIG. 4

FIG. 5

RECEPTACLE ATTACHMENT FOR WHEELCHAIR ARM

BACKGROUND OF THE INVENTION

1. Field of the Invention

The present invention relates to receptacle attachments for wheelchair arms.

2. Description of the Prior Art

A handicapped person in a wheelchair often has no convenient place to store articles of a personal nature. Loose containers, purses or the like fall out of reach or are not conveniently accessible. Alternatively, if a bag or similar holder is attached to the wheelchair where it can be reached there is the danger that it might become entangled in the moving parts of the wheelchair.

SUMMARY

According to the present invention, a receptacle attachment is provided which includes a case for mounting in fixed position upon a wheelchair arm, the walls 20 of the case defining a main compartment for receiving sundry articles. The receptacle attachment also includes a cover which in its vertical or closed position closes the main compartment, but which is quickly and easily pivoted to a horizontal or open position to define an auxiliary compartment. In the open position the cover engages upon the front wall of the case for support to bear the weight of beverage cups and like articles temporarily placed in the auxiliary compartment.

The receptacle attachment includes resilient means engaged between the case and cover to frictionally constrain the cover against inadvertent movement to its open position. However, a firm pressure upon the cover overcomes this resilient constraint to pivot the cover to its open position.

The present receptacle attachment is relatively inexpensive to manufacture, easy to maintain, and sufficiently rugged and dependable in service that a reliable and convenient receptacle is always at hand for the wheelchair user.

Other objects and features of the invention will become apparent from consideration of the following description taken in connection with the accompanying drawings.

BRIEF DESCRIPTION OF THE DRAWINGS

FIG. 1 is a perspective view of the receptacle attachment in closed position, mounted to the wheelchair arm;

FIG. 2 is a perspective view similar to FIG. 1, but illustrating the open position;

FIG. 3 is a view taken along the line 3-3 of FIG. 1;

FIG. 4 is a view similar to FIG. 3, but illustrating the open position; and

FIG. 5 is a view taken along the line 5-5 of FIG. 3.

DESCRIPTION OF THE PREFERRED EMBODIMENT

According to the present invention there is provided a receptacle attachment 10 for mounting to the outside of a wheelchair arm 12. The attachment 10 is preferably made of injection molded impact resistant plastic material and comprises, generally, a generally rectangular case 14 which is secured to the wheelchair arm 12 by an upper bracket 16 fitted to the arm support tube 13 and by a lower bracket 18 fitted to the wheelchair skirt panel or guard 20. The attachment 10 fur-

ther includes a cover 22 which is mounted to the case 14 for movement about a horizontal pivot axis 24, the cover normally being constrained against pivotal movement relative to the case 14 by a pair of snubbers 26.

5 The brackets 16 and 18 for mounting the attachment 10 to the wheelchair arm structure is merely exemplary, and various types of attachment brackets may be used, depending upon the particular nature of the wheelchair structure to which the receptacle attachment 10 is to be mounted. In the present example, the wheelchair arm 12 comprises the support tube 13, which constitutes the upper portion of the arm 12, and the skirt guard 20 which forms part of the lower portion of the arm 12.

15 The upper bracket 16 includes a vertical wall 28 which is integral with an upwardly opening, arcuate channel 30 adapted to complementally receive the arcuate undersurface of the arm support tube 13, as best illustrated in FIG. 1. The vertical bracket wall 28 includes openings within which a pair of interiorly threaded bushings (not shown) are press fitted. A pair of complementary mounting screws and washers 32 extend through suitable openings 34 in a vertically oriented rear wall 36 of the case 14, being threaded into the threaded bushings to rigidly secure the portion of the case 14 to the arm support tube 13.

The lower bracket 18 includes a vertical wall 38 having spaced apart openings within which are press fitted internally threaded bushings which threadably receive 30 a pair of complementary mounting screws and washers 40. These extend through suitable openings 42 provided in the case rear wall 36. Adjacent the wall 38 the bracket 18 includes a downwardly opening groove or channel 44 which complementally fits over the upper edge margin of the wheelchair skirt guard 20, so that tightening of the screws 40 securely clamps the case 14 onto the skirt guard 20 of the arm 12.

The openings 42 are vertically elongated to provide some tolerance for possible variations in the exact location of the upper edge of the skirt guard 20. However, it will be apparent that the location and number of the openings in the casing wall 36 can be made such as is required to adapt the receptacle attachment 10 to various types and sizes of wheelchair.

45 The case 14 further includes a horizontal bottom wall 46, a front wall 48 extending upwardly approximately one-third the height of the rear wall 36, and a pair of side walls 50 whose front or outer edges slope upwardly and inwardly as illustrated. The case walls 36, 46, 48 and 50 define a main compartment 54 for receiving and storing sundry articles, such as handkerchiefs, glasses, lipstick, and the like.

The upper portions of these side walls 50 include 55 openings within which the snubbers 26 are located. Each snubber is preferably a rubber grommet with a peripheral groove to seat the edge margin of the opening within which it is disposed. The portions of the snubber projecting outwardly of the opening are thus adapted to resiliently or frictionally engage the cover 22, as will be seen.

The lower portions of the case side walls 50 include 60 openings which receive a pair of trunnions 52. These are integral with the cover 22, as will be seen, and define the pivot axis 24. The inner terminus of each trunnion 52 includes a circumferential flange larger than the opening in the associated case side wall so that the trunnion 52 cannot come out of the opening. In addition,

tion, the case front wall 48 includes an outwardly projecting flange 51 at its upper edge to strengthen the front wall 48 against bending.

As best seen in FIG. 1, the cover 22 is pivotally mounted to the case 14 for movement between a vertical or closed position and a horizontal or open position. The cover 22 includes a front wall 56, a top wall 60 and a pair of side walls 62. In the closed position the cover walls 56 and 62 are generally parallel to the case walls 48 and 50, respectively, with the cover top wall 60 10 overlying the main compartment 54. In the open position the cover front wall 56 is horizontally oriented and forms the bottom of an auxiliary compartment 64 in which additional articles can be temporarily placed, such as beverage cups or the like. The auxiliary compartment 64 is formed on its sides by the case front wall 48 and the cover top and side walls 60 and 62.

The front wall 56 includes a lower terminus or edge portion in the form of an inwardly projecting flange 58 which, in the closed position of the cover 22, is located 20 adjacent to, coextensive with, and beneath the outwardly projecting flange 51 of the case 14. The flange 58 strengthens the cover wall 56 against bending and also cooperates with the case flange 51 to properly locate the cover 22 in its closed position, preventing inward or closing movement of the cover 22 beyond a predetermined point. Moreover, in the open position of the cover 22 the cover flange 58 engages the lower portion of the cover front wall 48 and constrains the cover 25 against further downward pivotal movement, thereby providing a secure support to bear the weight of filled beverage cups or the like in the auxiliary compartment 64.

Annular, upwardly projecting ridges or rings 66 are preferably integrally molded in the inner face of the 35 cover front wall 56 to bound and thereby locate the bottom rim of a beverage cup. In this regard, the cover front wall 56 includes an outwardly projecting hollow flange 68 which forms a groove or channel on the inside at the juncture of the front wall 56 and top wall 60 40 adjacent the auxiliary compartment 64. This channel is adapted to help contain some of the liquid spillage which may occur in the compartment 64. The hollow flange 68 also rigidifies the top wall 60 against deflection, so that a user can simply press down and outwardly upon the cover top wall 60 to quickly and easily 45 pivot the cover 22 to its open position, and it also rigidifies the cover front wall 56 against deflection so that the wall 56 can support the weight of filled beverage cups or the like.

The portions of the snubbers 26 projecting outwardly of the case side walls 50 are resiliently engaged by the

complemental inner surfaces of the cover side walls 62 in the closed position of the cover 22. The resilience and degree of projection of the snubbers 26 holds the cover 22 in its closed position and requires a deliberate and firm downward and outward force upon the cover 22 to move it to its open position.

From the foregoing it will be apparent that the present receptacle attachment 10 is relatively quickly and easily attached in a readily accessible position on a wheelchair arm. It defines a normally closed main compartment 54, and can be easily operated to open the main compartment 54 and simultaneously form an auxiliary compartment 64.

Various modifications and changes may be made 15 with regard to the foregoing detailed description without departing from the spirit of the invention.

I claim:

1. Receptacle attachment for wheelchair arm, said attachment comprising:
a case including means for mounting said case in fixed position upon a wheelchair arm, said case including a back wall, a bottom wall, a pair of side walls, and a front wall defining a main compartment for receiving sundry articles;
a cover including a front wall having a lower edge portion, a top wall, and a pair of side walls, said cover being pivotally mounted to said case for movement between a vertical, closed position, wherein said side walls and front wall are generally parallel to said side walls and front wall of said case with said top wall overlying said main compartment, and a horizontal, open position, wherein said front wall is horizontally oriented to define an auxiliary compartment defined by said front wall of said case and said front, top and side walls of said cover, said lower edge portion of said front wall of said cover engaging said front wall of said case in said open position to constrain said cover against pivotal movement below said horizontal open position, said front wall of said cover including an outwardly projecting upper portion defining, with said top wall of said cover, a channel adjacent said auxiliary compartment to receive spillage of any liquid in said auxiliary compartment and to rigidify said outwardly projecting upper portion of said front wall of said cover; and
resilient means engaged between said side walls of said case and said side walls of said cover and frictionally constraining the respective said side walls against relative movement in said closed position to releasably hold said cover in said closed position.
